UNITED STATES PATENT OFFICE.

JOHN BARTNICKI, OF NASHVILLE, ILLINOIS.

TRACTOR.

Application filed February 9, 1926. Serial No. 87,963.

This invention relates to tractors and has special reference to a tractor construction enabling an ordinary horizontal engine of the gas engine or steam engine type to be used in connection with a tractor.

One important object of the invention is to improve the general construction of devices of this description.

A second important object of the invention is to provide improved means, in such a tractor, for clutching the drive wheels to the driven axle.

A third important object of the invention is to provide improved means for tensioning the belt which connects the tractor driving mechanism with the engine.

A fourth important object of the invention is to provide improved braking means for such a tractor.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation from the right hand side of a machine constructed in accordance with this invention.

Figure 2 is a similar side elevation from the left hand side.

Figure 3 is a plan view of the complete machine.

Figure 4 is a plan view of the chassis of the machine with the engine and other parts removed.

Figure 5 is a detail front elevation of the front part of the machine.

Figure 6 is a detail elevation view, partly in vertical section, of the rear part of the machine.

Figure 7 is an enlarged section on the line 7-7 of Figure 6, the view being partly diagrammatic.

Figure 8 is an enlarged detail section on the line 8-8 of Figure 3.

In the construction of this invention there is provided a pair of side frame members 10 which are connected at their ends by transverse frame members 11. These side frame members are parallel to each other and the front part of each side frame member is lower than the rear part thereof. Beneath

the front ends of the side frame members 10 is located a bolster 12 which supports suitable bearings or a shaft or axle 13 carrying the forward wheels 14. Also on the front ends of the members 10 is supported a tool box 15 provided with a suitable lock 16. The rear axle 17 is supported in bearings 18 carried by the side frame members 10 and on this rear axle are mounted the traction wheels 19.

Mounted on the rear of the frame is an ordinary horizontal engine 20, the same being preferably an oil or gasoline engine and having the usual crank or main shaft 21 provided with the fly wheels 22. On one end of the shaft 21 is revolvably mounted a belt pulley 23 and this belt pulley carries one member 24 of a clutch while the other member 25 of said clutch is splined on the shaft 21 and is controlled by a lever 26 reaching back to the driver's seat 27 and working over a notched bar 28. On the frame members 10 are mounted bearings 29 which support a counter shaft 30 carrying a belt pulley 31 connected to the pulley 23 by a belt 32. At 33 is a lever which carries at one end an idler 34 acting as a tightener for the belt 32. The other end of this lever is connected by a spring 35 with a lever 36 movable between the full and dotted line positions of Figure 2 to release or tension the spring at the will of the operator. Thus when the tension is released the shaft 30 will be idle and the engine may be belted to any desired mechanism.

The pulley 31 is provided on one side with a clutch member 55 which is engageable by a clutch member 56 controlled by a rod 47 and splined to the shaft 30, the pulley being rigidly mounted on a hollow counter-shaft or sleeve 58 whereon is journaled a clutch member 59 engageable by a clutch member 60 keyed on shaft 58 and operated by a shipper 61 fixed to the rod 47. The bar 47 has near one end an arm 48 whereto is connected one end of a link 49 of a toggle or knee joint, the other link 50 of such joint being pivoted to a bracket 51 fixed to one of the members 10. These links are, of course, pivotally connected and to the joint of the links is pivoted a rod 52 which extends back adjacent the driver's seat and is provided with notches 53 selectively engageable with the rear frame member 11. The clutch member 60 is so arranged that it is engageable with the clutch member 59 at the time when

the members 55 and 56 are disengaged. Journaled on the sleeve 58 is a sprocket 62 which is rigid with clutch member 59 and connected by a chain 63 with a sprocket 64 mounted on one section of a differential shaft 65, whose sections are connected by an ordinary differential 66. Each outer end of the shaft 65 carries a sprocket 67 which is connected by a chain 68 to the sprocket 10 wheels 69 mounted on the drive shaft 17. One of the sprockets 69 is fixed to the drive shaft and the respective ground wheel 19. The other sprocket 69 is fixed to the remaining ground wheel 19 but revolves with said wheel on the shaft 17. The last mentioned sprocket carries a clutch member 70 which is engageable by the clutch member operated by a lever 72. On the shaft 30 is a belt pulley 73.

20 In operation, it will be seen that with the engine running the shaft 30 may be driven by moving the rod 47 in one direction, the sprocket 62 being idle. Thus farm machinery can be driven by the belt pulley 73. Upon moving the rod 47 to engage the clutch members 59 and 60 the shaft 65 will be driven and with clutch element 71 disengaged this will give a differential drive of the ground wheels 19. Thus the tractor 25 moves from place to place and may be guided by suitable steering means as indicated at 73^a, the wheels 19 moving independently by reason of the differential 66. However, in the event of tractor getting in such 30 ground that one ground wheel slips the clutch element 71 is engaged with clutch element 70, and the rear axle 17 is driven so that the two ground wheels operate together thus pulling the tractor out of its bad position.

There has thus been provided a simple and efficient device of the kind described and for the purpose specified.

It is obvious that minor changes may be 45 made in the form and construction of the invention without departing from the material spirit thereof. It is not, therefore, desired to confine the invention to the exact form herein shown and described, but it is 50 desired to include all such as properly come within the scope claimed.

Having thus described the invention, what is claimed as new, is:

- 55 1. In a tractor, a frame having a rear driver's seat and provided with pairs of front steering and supporting wheels and independently rotatable rear driving and supporting wheels, a horizontal engine mounted upon the rear end portion of the frame and having a transverse drive shaft at its forward end, a transverse counter shaft journaled on the frame forwardly of and below said drive shaft, manually releasable driving connections between said drive shaft and said counter shaft, a sectional transverse

shaft journaled on the frame below the drive shaft and between the counter shaft and the axle of the rear wheels, a differential gearing between the sections of said sectional shaft, driving connections between said counter shaft and one section of said sectional shaft, and constant driving connections between the sections of said sectional shaft and the respective rear driving and supporting wheels. 75

2. In a tractor, a frame having a rear driver's seat and provided with pairs of front steering and supporting wheels and independently rotatable rear driving and supporting wheels, a horizontal engine 80 mounted upon the rear end portion of the frame and having a transverse drive shaft at its forward end, a transverse counter shaft journaled on the frame forwardly of and below said drive shaft, manually releasable driving connections between said drive shaft and said counter shaft, a sectional transverse shaft journaled on the frame below the drive shaft and between the counter shaft and the axle of the rear 85 wheels, a differential gearing between the sections of said sectional shaft, driving connections between said counter shaft and one section of said sectional shaft, constant driving connections between the sections of said sectional shaft and the respective rear driving and supporting wheels, said first named counter shaft being hollow, a second transverse counter shaft upon which said first named counter shaft is journaled, manually operable means to connect said drive shaft to said second counter shaft and simultaneously disconnect said drive shaft from said first named counter shaft or vice versa, and means to facilitate transmission 90 of power from said second counter shaft to other machinery. 95

3. In a tractor, a frame having a rear driver's seat and provided with pairs of front steering and supporting wheels and independently rotatable rear driving and supporting wheels, a horizontal engine mounted upon the rear end portion of the frame and having a transverse drive shaft at its forward end, a transverse counter shaft journaled on the frame forwardly of and below said drive shaft, manually releasable driving connections between said drive shaft and said counter shaft, a sectional transverse shaft journaled on the frame below the drive shaft and between the counter shaft and the axle of the rear 100 wheels, a differential gearing between the sections of said sectional shaft, driving connections between said counter shaft and one section of said sectional shaft, constant driving connections between the sections of said sectional shaft and the respective rear driving and supporting wheels, said first named counter shaft being hollow, a second 105 transverse counter shaft upon which said first named counter shaft is journaled, manually operable means to connect said drive shaft to said second counter shaft and simultaneously disconnect said drive shaft from said first named counter shaft or vice versa, and means to facilitate transmission 110 of power from said second counter shaft to other machinery. 115

120 125 130

- transverse counter shaft upon which said first named counter shaft is journaled, manually operable means to connect said drive shaft to said second counter shaft and simultaneously disconnect said drive shaft from said first named counter shaft or vice versa, and means to facilitate transmission of power from said second counter shaft to other machinery, said last named manually operable means embodying a wheel rigid with the hollow counter shaft and geared to the drive shaft, a second wheel journaled on the hollow counter shaft and geared to the section of the sectional shaft, a clutch to connect the first wheel to the second counter shaft, a clutch to connect the hollow counter shaft to the second wheel, and means to simultaneously release either clutch and engage the other.
4. In a tractor, a frame having a rear driver's seat and provided with pairs of front steering and supporting wheels and independently rotatable rear driving and supporting wheels, a horizontal engine mounted upon the rear end portion of the frame and having a transverse drive shaft at its forward end, a transverse counter shaft journaled on the frame forwardly of and below said drive shaft, manually releasable driving connections between said drive shaft and said counter shaft, a sectional transverse shaft journaled on the frame below the drive shaft and between the counter shaft and the axle of the rear wheels, a differential gearing between the sections of said sectional shaft, driving connections between said counter shaft and one section of said sectional shaft, and constant driving connections between the sections of said sectional shaft and the respective rear driving and supporting wheels, a rotatable rear axle having one of said rear driving and supporting wheels fixed thereon and the other journaled thereon, and manually operable means to clutch said other wheel to or disconnect the same from said rear axle, at will.
- In testimony whereof I affix my signature.

JOHN BARTNICKI.
